6 Claims. (Cl. 183—90)

This invention relates to apparatus for separating solid particles from air or other gases.

It is a particular aim of the present invention to provide means for facilitating the flow of the material to be separated, to the collecting chamber, through novel means which diminishes the pressure in the collecting chamber with respect to the pressure in the separating chamber.

The more specific objects and advantages will become apparent from a consideration of the description following taken in connection with accompanying drawing, illustrating an operative embodiment.

In said drawing:

Fig. 1 is a view of the apparatus in side elevation;

Fig. 2 is a left hand end elevation thereof, and

Fig. 3 is a side elevation of a modified form of the apparatus.

Referring specifically to the drawing wherein like reference characters designate like or similar parts in the different views, 1 designates a separating drum or chamber which is cylindrical and of maximum internal area at its receiving end, which may be extended by a cylindrical preseparatory 3. The inlet is shown at 4 and is tangentially disposed and provided in the wall 1 or extension thereof as shown in Fig. 1. Disposed across the outer end of preseparatory 3 is a plate 24. Disposed concentrically in the drum 1 and extending partly outwardly beyond the plate 24 is a cylindrical outlet pipe 5, fastened interiorly of the drum by a support 12 suspended from the upper portion of the drum.

Said drum 1 at its rear end portion as shown at 2 is conical so that the incoming gases will rotate and move longitudinally along the inner surface of the drum 1 with the path progressively decreasing in diameter at said portion 2.

Substantially centrally and longitudinally in the lower portion of the wall of portion 2 is an escape slit or opening 19 for solid particles, which slit or opening may be of uniform breadth throughout or be V-shaped as shown, with its larger end remote from the inlet 4.

Side walls, preferably flaring downwardly slightly, at 25 and 26 and corresponding front and rear walls 27, rest on and are secured to a collecting chamber 10, making an air tight connection between the same and the separating drum. Such collecting chamber is normally closed by a suitable outlet means at 11.

At the smaller end 7 of drum portion 2 is a pipe 8 centrally of which a pipe or conduit 17 is connected having a discharge end at 18 in-

teriorly of conical drum portion 2. Said pipe or conduit 17 extends through the rear wall 27 at one side of the drum, having an inlet end 16 at the top of the collecting chamber or space adjacent wall 25, such pipe 17 at its inlet end preferably being bevelled as shown.

Adjacent said inlet end 16, a chink or slot 21 is provided in slightly oblique direction in the wall of drum 1 by a struck-out portion 23 thereof, such chink being disposed to produce an ejector effect.

Said conduit or pipe 17 at inlet 16 may be provided with means to set the aspirated gas in rotation, such for instance, as the scoops 22.

The device described operates in the following manner:

The gas bearing solid particles to be separated enters at the inlet 3 at the end of the drum or separator having the greatest cross section and it is forced to pass through the separator with simultaneous rotary and longitudinal movement with an increasing angular velocity by virtue of the diminishing of the cross section of the path of flow at conical part 2. Under the rotary phase of such movement the outer layer of the gas stream containing the particles to be separated falls through the outflow slit 19 into the collecting chamber 10 which is closed with respect to the atmosphere and in which chamber the particles settle. The gas led to the collecting chamber flows therefrom at 16 into pipe 17 and thence through the pipe 17 to the outlet 18 and into the conical part 2 of the separator or drum by virtue of the lesser pressure in that part of the separator, where the main volume of the gas changes its helical movement into a longitudinal one and at 6 enters the outlet pipe 5. The collecting chamber 10 also being connected with the end of the separator or drum 1 nearest to the gas inlet 3 or with the preseparatory 3 by means of the ejector slit 21, a flow of gas will take place from the collecting chamber or drum and also through this slit owing to the fact that the pressure in the collecting chamber 10 is greater than in the preseparatory 3 or that part of the separator which has the greatest cross sectional area, but less than the pressure in the conical end 2 of the separator, where the gas flows through the outflow slit 19 to the collecting chamber 10.

Various changes may be made within the spirit and scope of the invention, and for instance the modified form of Figure 3 may be used. This form differs from the preceding form only in omitting the preseparatory. The outlet pipe here designated 105 extends into the conical part 102.

of the drum, the truly cylindrical portion thereof being omitted. The drum 102 is supported on the collecting chamber 110 which is of a conformable size. The operation is the same as in 5 the preceding form, and otherwise the structure is the same.

What is claimed is:—

- 10 1. Apparatus for separating solid particles from gases consisting of a separating drum, having at one end a considerably larger cross sectional area than at the other end, and having a portion progressively diminishing toward the latter end, a substantially central gas outlet at the first mentioned end, a collecting chamber for 15 the solid particles, the separator having an outflow slit for the separated particles communicating with the collecting chamber, the particles being separated by the gas being forced to follow, under rotation, the progressively diminishing 20 diameter of said portion and then in purified form escape through said outlet, and means providing communication between the smaller end of said portion and the inlet end of the collecting chamber so that the gas rotating under pressure 25 in said smaller end produces a suction in the said means in the direction towards the separator chamber, by which means the over-pressure in the collecting chamber is diminished and consequently the flow through the said slit is increased 30 30 in the direction to the collecting chamber.
2. Apparatus for separating solid particles from gases consisting of a separator drum having a pre-separator at one end thereof, said end being of considerably larger cross-sectional area than 35 the other end, said separator having a conical portion diminishing in size toward the other end, a substantially central gas outlet at the first mentioned end, the wall of said portion having

an outflow slit for the separated particles communicating with the collecting chamber, the particles being separated by the gas being forced to follow, under rotation, the progressively diminishing diameter of said portion and then in purified form escape through said outlet and means providing communication between the smaller end of said portion and the inlet end of the collecting chamber so that the gas rotating under pressure 10 in the said means in the direction towards the separator chamber, by which means the over-pressure in the collecting chamber is diminished and consequently the flow through the said slit is increased 15 in the direction to the collecting chamber. 5

3. Device as claimed in claim 1, wherein said means has scoops to set the aspirated gas in rotation.

4. Device as claimed in claim 2, wherein said 20 means has scoops to set the aspirated gas in rotation.

5. Device as claimed in claim 1, wherein the separator chamber and the collecting chamber communicate by means of an ejector opening 25 near the larger end of the separator chamber so that the incoming gas produces a suction from the collecting chamber in the direction to the separator chamber.

6. Device as claimed in claim 2, having the pre- 30 separator connected with the collecting chamber by means of an ejector opening adjacent the gas inlet end of the device, so that while the gas rotates in the pre-separator a suction is produced from the collecting chamber in the di- 35 rection to the pre-separator.
